UNITED STATES PATENT OFFICE.

FRED C. SCHOENTHAL, OF BUFFALO, NEW YORK.

DISK WHEEL.

1,389,601.

Specification of Letters Patent.

Patented Sept. 6, 1921.

Application filed March 23, 1920. Serial No. 368,094.

To all whom it may concern:

Be it known that I, FRED C. SCHOENTHAL, a citizen of the United States, residing at Buffalo, in the county of Erie and State of New York, have invented certain new and useful Improvements in Disk Wheels; and I do hereby declare the following to be a full, clear, and exact description of the same, such as will enable others skilled in the art 10 to which it appertains to make and use the same, reference being had to the accompanying drawings, and to figures of reference marked thereon, which form part of this specification.

15 Like figures of reference refer to like parts.

This invention relates to disk wheels, particularly to that kind thereof in which a single disk forms the main part of the wheel.

20 One of the objects of this invention is to provide a disk wheel of the single plate disk type, having the main part of the wheel including a rim support and a section of the rim of one piece of sheet metal, reinforced 25 by a smaller disk having peripheral contact with the larger disk midway of the center and rim of said larger disk, and diverging from the same to form a reinforcing brace to the larger disk, while seated in a specially formed flange of the hub in a manner 30 to incorporate the seating features with the hub flange to obviate the necessity of an extra seating piece, such as is shown in my application of Serial Number 319,396, filed 35 August 23, 1919.

A further object is to provide at the hub a plurality of spacing and flanged bolts which will give the necessary torsional resistance to the parts connected with the hub, at the 40 same time holding these parts in proper spaced relation.

A further object is to provide reinforcing pieces at the rim section where riveted to the ring portion, having these reinforcing pieces 45 ribbed on their edges to stiffen the same.

A further object of this invention is to provide a single disk wheel which is partly reinforced, and which is formed into a rim support and section of the rim having connected therewith an annularly recessed ring portion, in which a split ring is positioned 50 to complete the rim for holding the tire thereon.

With these and other objects my invention 55 consists in certain construction, one embodiment of which is illustrated in the drawings,

is hereinafter described, and what I claim is set forth.

In the drawings,

Figure 1 is a front elevation of a single 60 disk wheel embodying my invention, partly broken away, illustrating the relation of the various members incorporated with the disk.

Fig. 2 is a section taken on the line X—X of Fig. 1, and shows the construction of a 65 driving wheel on a keyed shaft.

Fig. 3 is a rear elevation of a wheel similar to that shown in Figs. 1 and 2 in construction, but varying therefrom in the formation of the hub, which is adapted for front wheel 70 purposes of an automobile.

Fig. 4 is a section taken on the line A—A of Fig. 3 and shows the construction of a wheel similar to that shown in Figs. 1 and 2, but differing in the formation of the hub. 75

Fig. 5 is a front elevation of the hub shown in Fig. 4.

Fig. 6 is a section similar to that shown in Fig. 4, and here taken on the line Y—Y of Fig. 5. 80

Fig. 7 is a front elevation of the reinforcing disk shown in Figs. 2, 3, and 4.

Fig. 8 is a section of the reinforcing disk shown in Fig. 4, and here representing the section taken on the line Z—Z of Fig. 7. 85

Fig. 9 is a perspective view of the bridging piece shown in Figs. 3 and 4.

Fig. 10 is a rear elevation of a wheel similar to that shown in Fig. 3, but having out-turned rim flanges and a modified form 90 of rim section.

Fig. 11 is a section taken on the line B—B of Fig. 10.

Fig. 12 is an enlarged section of the rim shown in Fig. 11. 95

In the figures, referring particularly to Figs. 1 and 2, which illustrate the driven or rear wheel, there is shown upon the shaft 1, a hub 2 secured rotatively thereon by the key 3. The hub 2 has a flange 4 near the periphery of which is formed an annular seat 5, having integral therewith the brake flange 6. The hub 2 has an annular shoulder 7, against which is positioned the reinforcing disk 8 which is bent into a cylindrical portion 9, which merges into a short flat portion 10, resting against the annular ridge 11 of the flange 4. The flat portion 10 merges into a conical portion 12, which in turn merges into another conical portion 13, 11 forming an annular elbow at 14, with the conical portion 12, fitting into the annular

seat 5 of the flange 4. The conical portion 13 merges into another conical portion 15 at the annular bend 16, and terminates in an annularly grooved peripheral portion 17. This disk is similar in construction to that shown in my co-pending application of Serial Number 319,396, filed August 23, 1919, but in this case resting in a seat against the flange of the hub, rather than in an extra adapting piece. Positioned in contact with the portion 8^a of the disk 8 is the large disk 18, which in section has an ogee curve. The portion 15 of the disk 8 is in contact with the portion 15^a between the curves of the disk 18. This disk 18 is formed into a rim support 19, and a rim portion 20, projecting inwardly from which is the short tube 20^a, for receiving the tire valve. The support 19 has a flat part 21 against which is riveted an annularly recessed rim section 22, by the rivets 23, which pass through bridging pieces 23^a, reinforcing the support. Fitting into the recess of the ring 22 is the inturned flange 24 of the split rim ring 25. Referring back to the hub 2, there are shown three spacing bolts 26, which hold the flat portion 8^a of the reinforcing disk 8, together with the disk 18 and the plate 27 all in fixed spaced relation from the flange 4. The spacing bolts 26 have flanges 28, which serve to make the connection between the wheel parts and the flange 4 rigid, particularly against torsional strains. To further strengthen the wheel, I provide the ring 29 shaped to co-fit the inner surface of the reinforcing disk 13, and to act also as a spacer between it, and the disk 18.

Referring now, to the form of wheel shown in Figs. 3 and 4, the hub 2^a is constructed to adapt it to idly turn upon the shaft, and the parts of this wheel are similar to those shown in Figs. 1 and 2, and similarly numbered, with the exception that the rear flange 6^a is much smaller than the flange 6, shown in Fig. 2, and is not used for braking purposes. Referring now to the particular construction of the bridging piece 23^a, as shown particularly in perspective in Fig. 9, there are stiffening ribs 23^b stamped into the sheet metal at the side edges of the piece 23^a.

Referring now to Figs. 10, 11 and 12, the construction of the disks, the wheel portions next the hub, and the part of the rim is similar to that shown in Fig. 2, with the exception that the flanges of the rim are turned outward. The split ring 30 forming one of the flanges of the rim of the wheel, has an L-section. This ring with the remaining portion of the rim and another ring into which it fits, is better shown in section in Fig. 12, wherein an inclined flange 31, is shown fitting into a groove 32, in a ring 33, which ring 33 is held by bolts 34 to the felly portion of the wheel. The split ring 30 has a flat portion 35, the outer surface of which forms a continuation to the surface 36 of the rim portion which is integral with the disk 18. The flat portion 35 of the ring 30 has a beveled portion 37, lying against a corresponding beveled part of the other portion 70 of the rim. The inclined flange 31, is conically converged away from the center of the wheel, and when in a position held by the inflated tire T, it occupies the outer part of the annular recess 32 having the periphery 75 31^a of the flange 31 in contact with the surface of the annular groove 32, while at the same time the hook portion 33^a of the ring 33 is in contact with the flange 31 near the bend of the L-section of the split ring 30. It will be observed that there is a space back of the flange 31 in the annular groove 32 sufficiently large to permit of the split ring 30 being moved toward the center of the wheel after the tire has become deflated, so that 80 the edge 31^a of the flange 31 passes radially outward over the edge 33^a of the ring 33 in removing the split ring 30. After the parts are in place, as shown in Fig. 12 with the tire T under pressure of inflation, the flange 90 31 is in abutting relation with the ring 33 at the zone 31^a, preventing any outward movement of the split ring 30, while at the same time, on account of the conical formation of the flange 31, the edge 33^a of the ring 95 33 forms a positive locking engagement with the split ring 30, against any radially outward movement of the ring 30, from the ring 33. The purpose of the beveled portion 37, of the ring 30 is to provide a shouldered fit of the parts when in place, and at the same time permit of the easy movement of the ring 30 toward the place of the tire, 100 while removing the same.

Considering the spacing bolts 26, the flanges 28 thereof being comparatively large in diameter, present substantial spacing surfaces between the hub portion parts of the wheel at the same time resist any turning out of their right angle position to the hub plate, 110 on account of the breadth of the flanges 28.

Having described my invention, I claim—

1. In a sheet metal disk wheel having a hub and a hub flange, said hub flange having an annular recess near its periphery forming a circumferential seat, an auxiliary disk in shouldered engagement with said seat, and a main disk spaced from said auxiliary disk at the contact of the latter with said seat and in fixed contact with said auxiliary disk near the periphery of said auxiliary disk. 115
2. In a sheet metal disk wheel having a hub and a hub flange, said hub flange having an annular recess near its periphery forming a circumferential seat, an auxiliary disk in shouldered engagement with said seat, a main disk spaced from said auxiliary disk at the contact of the latter with said seat and in fixed contact with said auxiliary disk 120
3. In a sheet metal disk wheel having a hub and a hub flange, said hub flange having an annular recess near its periphery forming a circumferential seat, an auxiliary disk in shouldered engagement with said seat, a main disk spaced from said auxiliary disk at the contact of the latter with said seat and in fixed contact with said auxiliary disk 125
4. In a sheet metal disk wheel having a hub and a hub flange, said hub flange having an annular recess near its periphery forming a circumferential seat, an auxiliary disk in shouldered engagement with said seat, a main disk spaced from said auxiliary disk at the contact of the latter with said seat and in fixed contact with said auxiliary disk 130

near the periphery of said auxiliary disk, a rim support at the outer edge of said main disk, and a rim section fixed to said support.

- 5 3. In a sheet metal disk wheel having a hub and a hub flange, said hub flange having an annular recess near its periphery forming a circumferential seat, an auxiliary disk in shouldered engagement with said seat, a
- 10 main disk spaced from said auxiliary disk at the contact of the latter with said seat and in fixed contact with said auxiliary disk near the periphery of said auxiliary disk, said main disk having a hollow zone near its periphery concave on the face of the wheel and having a convex zone on the face of said wheel adjoining the hub section thereof, and means for holding the parts of the wheel together.
- 15 4. In a sheet metal disk wheel for vehicles, a hub, a main disk fixed to said hub forming the body of the wheel, a flange on said hub, an annular seat near the periphery of said flange, a sheet metal auxiliary bracing disk adapted to fit into said seat, and 25 having a peripheral bearing contact with said main disk, and means for holding the parts of the wheel together.
5. In a disk wheel, the combination of a hub, a hub flange, an auxiliary disk bearing 30 against said flange adjacent its periphery, a plurality of spacers between said flange and said disk and means for securing said spacers thereto.
6. In a disk wheel, the combination of a 35 hub, a hub flange, a shoulder on said hub, a main disk and an auxiliary disk bearing against said shoulder and said flange adjacent its periphery.

FRED C. SCHOENTHAL.
